UNITED STATES PATENT OFFICE.

CHARLES OSCAR TRACY, OF NORWICH, CONNECTICUT.

SASH-CORD FASTENER.

1,248,038.

Specification of Letters Patent. Patented Nov. 27, 1917.

Application filed June 22, 1916. Serial No. 105,214.

To all whom it may concern:

Be it known that I, CHARLES OSCAR TRACY, a citizen of the United States, residing at Norwich, in the county of New 5 London and State of Connecticut, have invented certain new and useful Improvements in Sash-Cord Fasteners, of which the following is a specification.

This invention has as its object to provide an improved device for securing sash cords to window sashes and it is one aim of the present invention to provide a device of this class so constructed that the same will not be liable to split the wood of 10 which the sash is made. Ordinarily, such devices are provided with heads which are designed to be positioned within openings formed in the side members or stiles of the sash and these heads are formed with one 15 or more spurs designed to enter the walls of the openings. It has been found that devices of this type so constructed present the disadvantage that the spurs are liable to split the wood, thereby loosening the connection of the cord with the sash and preventing ready raising and lowering of the sash. The present invention, therefore, contemplates the provision of means for coaction 20 with the walls of the openings in the side members of the sash for limiting the entrance of the spurs into the wood and thereby obviating splitting of the wood or loosening 25 of the connection and at the same time rendering the connection between the device 30 and the sash more secure.

In applying devices of this nature to the ends of sash cords it is customary to lay the end of the cord in the device, grasping the head of the device in one hand and with 40 the other hand striking blows with a hammer or like implement to strike down the spurs of the device to cause the same to grip the said end of the cord. In a well-known type of such devices the spurs are 45 so located upon the head that the head cannot be grasped for the purpose above stated without likelihood of the spurs cutting into the fingers and, therefore, it is a further aim of the invention to so construct the present 50 device that the head thereof may be conveniently grasped and firmly held without any likelihood whatsoever of the fingers being injured by the spurs upon the head.

In the accompanying drawings:

55 Figure 1 is a side elevation of one of the

devices applied to a window sash and the weight cord therefor.

Fig. 2 is a perspective view of the device removed.

Fig. 3 is a top plan view thereof. 60

Fig. 4 is a view similar to Fig. 1, illustrating the use of the device in connection with a chain as distinguished from a weight supporting cord.

Fig. 5 is a similar view illustrating the 65 use of the device in connection with a tape.

The device embodying the present invention includes a body portion which is in the form of an open sleeve and substantially semi-cylindrical, this said portion being indicated by the numeral 1 and being formed at each lateral edge with a series of spurs indicated by the numeral 2, the spurs at the two edges being alternately arranged as clearly shown in Figs. 1 and 2 of the drawings. The spurs 2 preferably constitute continuations of the opposite side portions of the body 1 and it will be understood that in applying the device to a sash cord the end of the cord is laid within the concave side 70 of the body and the spurs 2 are struck down with a hammer or other suitable implement so as to firmly bind the cord in the manner shown in Fig. 1, the said cord being indicated by the numeral 3, or the device may be employed in connection with a chain indicated at 4 in Fig. 4 of the drawings, or a tape indicated at 5 in Fig. 5 of the drawings. After striking down the said spurs 75 in the manner stated, the cord, chain or tape, as the case may be, is laid within a groove 6 formed in the outer face of the stile of the window sash and this groove at its lower end communicates with a recess 80 formed in the said face of the stile and the wall of this recess is preferably cylindrical as shown in Fig. 1. At its lower end 85 the body 1 is formed with a neck 8 which projects from the convex side of the said body at the said end thereof at right angles 90 to the longitudinal axis of the body and this neck is provided with lateral extensions 9 integral with its lateral edges and the said extensions as well as the neck itself are 95 continuously and uniformly curved on the arc of a circle from end to end of the said extensions, the curvature being such that when the device is assembled with the stile 100 of the window sash, the convex upper side of the neck and its extensions 9 will fit 105

110

snugly against the upper side of the cylindrical wall of the opening 7, in the manner shown in Figs. 1, 4 and 5.

- At its end the neck 8 is provided with an integral head 10 which occupies a plane parallel to the longitudinal axis of the body 1 and which extends downwardly below the plane of the said neck and has an arcuate lower edge indicated by the numeral 11.
- 10 The upper edge of the head 10 is formed at its ends with upwardly and outwardly projecting spurs 12 which are preferably sharply pointed and which occupy the same plane as the said head. By reference to 15 Figs. 1 and 2 of the drawings, it will be observed that the extensions 9 of the neck 8 have their extremities terminating short of or within the arc described by the edge 11 of the head 10 and that when the device is 20 viewed in elevation the said extensions 9 at their end portions extend part way across the rear faces of the spurs 12, the said extensions being, however, spaced from the rear face of the head 10 and its said spurs.
- 25 It will also be observed by reference to Fig. 1 that the upper edge of the head 10 is not located directly at the juncture of the head with the neck 8 but that the upper edge of the said head is connected with the neck by 30 a short connecting portion 13 and, therefore, the upper edge of the head is located below the plane of the neck 8 and the spurs 12 may enter the upper side of the cylindrical wall of the recess 7 without such entering 35 being interfered with by the upper edge of the head although the engagement of the upper or convex side of the neck 8 and its extensions 9 with the said upper side of the said wall of the recess serves to limit the entrance of the spurs into the said wall of the recess.
- 40 From the foregoing description of the in-

vention it will be understood that when the device is applied to the stile of a window sash the upper or convex side of the neck 45 8 and the extensions 9 thereof will seat firmly and snugly against the upper side of the cylindrical wall of the recess 7 and will prevent the spurs 12 from entering so far into the wood as to be liable to split the same. 50 It will also be understood that the device embodying the present invention may be readily grasped between the thumb and forefinger of one hand while the device is being applied to the sash cord, chain or tape, the 55 thumb being disposed against that face of the head 10 which is presented toward the body 1 and within the concavity formed by the under side of the neck 8 and its extensions 9, the forefinger bearing against the 60 opposite face of the said head and the thumb and finger being in this manner enabled to firmly grasp the device without likelihood of either being injured by the spurs 12.

Having thus described the invention, what 65 is claimed as new is:

In a device of the class described, a clamping body provided with a neck extending rearwardly from its lower end at right angles to the plane of the rear side of the body 70 and thence downwardly at right angles and provided at its last-mentioned portion with a flat sided head occupying a plane at right angles to the plane of the first-mentioned portion of the said neck, the neck being provided 75 at the lateral edges of the said first-mentioned portion with extensions continuously curved laterally and downwardly, the said head at its upper edge being provided with upstanding spurs in rear of said extensions of the neck.

In testimony whereof I affix my signature.

CHARLES OSCAR TRACY. [L. S.]
